TABLE FOR STUDENT LEARNING

John Des Marais, 2626 Sheridan, and Roger A. Sinigoi,
3186 McKinley, both of Hollywood, Fla. 92644

Filed Apr. 18, 1969, Ser. No. 16,812

Term of patent 14 years

Int. Cl. D6—01

U.S. Cl. D33—14

FIG. 1

FIG. 2

FIG. 3

FIG. 1 is a top plan view of a table for student learning in accordance with the invention;

FIG. 2 is an elevational view of the table for student learning; and

FIG. 3 is a bottom plan view of the table for student learning.

The surfaces of the table which are not visible in the drawings are plain and unornamented.

We claim:

The ornamental design for a table for student learning, as shown and described.
